UNITED STATES PATENT OFFICE.

EDMOND HEUZÉ-BEAUREGARD, OF STE.-ADRESSE, FRANCE.

ADDRESSING MACHINE.

Application filed December 14, 1926, Serial No. 154,759, and in France December 8, 1925.

My invention has for its object to provide an addressing machine and it is more particularly designed for using thin stencils made for instance by a typewriting machine, such stencils being carried by convenient frames.

My said invention is more particularly characterized by the combination with a carrying frame of a guiding device containing a number of stencils, of a stencil catching and displacing mechanism, operating the said stencils one after the other, and of an inking device containing a quantity of ink and provided with a feeding device which may be conveniently regulated, thus embodying a portable unit which allows addresses to be easily printed with the use of stencils obtained by usual or other means.

In the accompanying drawings which show an example of a machine embodying the invention:

Fig. 1 is a diagrammatic front view of the machine according to my invention,

Fig. 2 is an end view of the same,

Fig. 3 is a cross section of the inking mechanism.

Fig. 4 is an end view showing the end of the machine opposite to that seen in Fig. 2.

Fig. 5 is a fragmentary elevation of a detail showing the operation of the inking mechanism.

Fig. 6 is a longitudinal vertical section of the machine.

The machine comprises a frame 1 provided with legs 2 for instance four in number which rest on a convenient support which may be for instance any piece of furniture such as an office table or even in the home. In such frame is provided a sliding casing 3 provided with an operating handle 4 (Fig. 1) said casing containing the inking and printing mechanisms.

In the upper part of such casing 3 is provided a chamber 5 forming an ink fountain and provided with a filling opening 6 which may be closed by a sliding or other closing device 7 (Figs. 1 and 3). Such chamber has in its bottom a regulable feeding opening 8 which may be regulated from outside by a knob 9 (Fig. 2) by means of which it is possible to regulate with all desired precision the quantity of ink falling upon a roller 10, which may be made of felt or of any other suitable substance and which is rotatably mounted in a movable frame 11 provided with a knurled

regulating knob 12 (Fig. 3). Such frame may comprise a return spring not shown acting in a direction opposed to that of the knob 12 and which roller 10 is designed to contact with a second roller 13 disposed above the inking pad 14 mounted on a spindle which carries outside the casing 3, a wheel 15 the periphery of which as shown in Fig. 1 comprises two toothed sections 16-17 diametrically opposed and interrupted and separated by flat portions 18-19. Arranged on one side of the frame 1 and just under the said wheel 15 is a directing path 20 including a middle portion having a number of teeth, or a rack 21 corresponding to toothed sections 16-17 of wheel 15, such rack 21 being located intermediate a flat horizontal portion 22 and an inclined portion 23.

Projecting from the casing 3 is a knob 24 designed to receive a hook, formed at one end of a connecting rod 25, the other end of which is pivotally mounted on a pin 26 rigid with a frame 27 slidably mounted in guide ways 28 (Figs. 2 and 4) which are provided on the frame 1. The frame 27 comprises a convenient recess of the same height as the stencils and allows the same to slide in the guide 28 in its longitudinal movements.

The complete machine is preferably pivotally mounted on pins 29 round which the said machine may be freely rocked, a locking device being composed of a pair of levers 30 provided with rollers and keyed on a common transverse shaft 31 provided with a return spring 32 which always tends to bring the said levers 30 to a disengaged position, allowing the said frame to oscillate, or rock on the pins. One of the said levers 30 carries a lug 33 arranged in front of the end of a rod 34 provided with a spring, and the other end of which is arranged in the path of an abutment 35 provided on the movable casing 3. A movable abutment 36 (Fig. 2) arranged for regulating the width of margin is provided on the frame of the machine, and a basket 37 (Fig. 1) which can be removed may be arranged on the end of the frame 1 for receiving the stencils after they have served their purpose.

The operation is as follows:

The several parts occupying the position shown in the drawing, and the receiver 28 being supplied with stencils of any suitable construction, the operator places at the printing point of the machine, in a split 38 provided for that purpose, an envelope, band or

sheet of paper which is to receive the impression. The operator grasps the handle 4 and moving the casing 3 in the direction of the arrow in Fig. 1 for bringing such casing in the position shown in the said Fig. 1 in which position a stencil falls from the magazine 28^a into the frame 27 integral with the casing 3 and provided for carrying the stencils. In such movement towards the right hand in the direction of the arrow in Fig. 1, the abutment 35 acts upon the rod 34 which brings the levers 30 having the rollers to the position of Figs. 1 to 4 which corresponds to the printing position of the machine. In then moving the casing 3 in the direction opposite to that of the arrow in Fig. 1, the lowermost stencil carried by the frame 27 is taken with such device and brought above the split 38.

20 During such backward movement of the casing 3 the flat part 18 of the toothed wheel 15 which has been brought in a horizontal position by the flat part 22 of the directing path 20 passes above the rack 21 without meshing with the same, the inking pad 14 occupying in such movements the position as indicated in Fig. 3 without having any contact with the displaced stencils. The casing having arrived at the end of its travel 25 on the left hand side of Fig. 1, the lower flat part 18 of the wheel 15 now comes into contact with the incline 23 which, as shown in Fig. 5, causes the said wheel 15 to partially rotate so that when such casing 3 is again moved in the direction of the arrow 30 in Fig. 1 for producing the impression, the first tooth 39 abuts against the first tooth of the rack 21 so that the mesh becomes completed, each tooth 17 meshing with the corresponding tooth of the rack 21 thus causing a rotation of the wheel 15 and of the inking pad 14 which is connected with the same. Such rotation is produced above the stencil while the operator applies with his hand 35 a certain pressure on the handle 4, so that the address provided on the stencil is reproduced or printed on the envelope, band or other sheet of paper which was introduced in the split 38.

50 The casing 3 being moved towards the left hand side, the spring 32 on shaft 31 which carries the levers 30 and causes the same to incline and cause the leaning of the frame 1 and cause it to drop, such position being resumed when the casing 3 comes back to the position of Fig. 1, while moving by its abutment 35 the end of the rod 34.

55 It is then easily seen that ordinarily every time the casing 3 is operated, a new stencil is brought into its position for impression, such impression being effected by the movement of the frame in the direction of the arrow in Fig. 1. The stencils after impression are projected into the basket 37.

60 When it is desired to repeatedly print from

the same stencil the operator unhooks or disconnects the connecting rod 25 thus preventing any movement of the frame 27 and upon turning a quarter of a revolution a knob 40 (Figs. 1 and 2) carrying an abutment 41 for 70 bringing the same into the position shown in dotted lines in Fig. 2 in the path of stencils 42, all movement of the said stencil is prevented and the said stencil remains in the position for printing. 75

The several parts will have any appropriate form and be made of any suitable substance calculated to reduce wear. The dimensions of the machine may of course vary according to its use. The above described 80 arrangement however allows the said machine to be embodied in a portable, very light form, the frame support being arranged for containing one or several drawers or similar devices for receiving the stencils. 85

The invention may be applied for the impression of addresses on envelopes or any surfaces and generally speaking for reproducing in any number a written substance 90 carried by stencils of appropriate dimensions.

The important particular of the present application is the combination with the directing path 20 of the partially toothed 95 wheel mounted on the shaft of the inking roller 14, whose teeth mesh with the fixed teeth 21 only during printing travel of the casing 3.

What I claim is:

1. An addressing machine comprising in combination, a supporting base, a longitudinal frame rockably mounted thereon, a magazine adapted to carry stencils in stacked relation, means guided in said frame for receiving and feeding the stencils consecutively to printing position, a reciprocable casing, releasably connected with the said stencil feeding means, a regulable ink fountain in the upper part of said casing, ink distributing rollers in said casing, spring controlled levers at one end of said rockable frame, an upwardly extending lug carried by one of said levers, an abutment on the said casing, a spring controlled rod slidably mounted on the frame and adapted to be operated by said abutment and co-acting with said lug to hold the frame in printing position, and a rotary ink pad mounted on a spindle in said casing, as and for the purpose set forth. 100 105 110 115 120

2. An address printing machine according to claim 1 characterized by the spindle of the inking pad being provided at its external end with a wheel having on its periphery two groups of teeth diametrically opposite each other and separated by flat portions and corresponds with a rack carried by a directing path secured to the frame which at its end corresponds to the beginning of printing, is provided with an in- 125 130

cline controlling the mesh of the teeth of such wheel whereby to determine the rotation of the inking pad and the inking of the stencils.

- 5 3. An addressing machine comprising in combination, a supporting base, a longitudinal frame rockably mounted thereon, means for holding a series of stencils in stacked relation, means guided in said frame for receiving and feeding the stencils consecutively to printing position beneath the frame, a reciprocable casing releasably connected with said stencil feeding means, ink feeding means within said casing, ink distributing rolls in said casing, a spindle in said casing and a rotary ink pad mounted thereon, said spindle extending exteriorly of the casing,

a toothed wheel mounted on said exterior end, said wheel consisting of toothed segments diametrically opposite each other, and separated by diametrically opposite flat portions, and a pathway for said wheel, attached to the front side of said frame and comprising a flat end portion, an intermediate toothed portion and an inclined end portion, the teeth of said toothed wheel being in mesh with the rack teeth only during printing travel of the mechanism, as and for the purpose set forth.

In testimony whereof I have hereunto set 30
my hand at Havre, France, this 30th day of
November, 1926.

EDMOND HEUZÉ-BEAUREGARD.
